UNITED STATES PATENT OFFICE.

EZRA T. WHITING, OF GREEN LAKE, WISCONSIN.

AIR-HEATER.

1,385,651.

Specification of Letters Patent. Patented July 26, 1921.

Application filed March 1, 1920. Serial No. 362,599.

To all whom it may concern:

Be it known that I, EZRA T. WHITING, a citizen of the United States, and resident of Green Lake, in the county of Green Lake

60

5 and State of Wisconsin, have invented certain new and useful Improvements in Air-Heaters; and I do hereby declare that the following is a full, clear, and exact description thereof.

65

10 My invention relates to new and useful improvements in air heaters, as disclosed in Patent No. 442,846 dated December 16th, 1890, and has particular reference to those devices which form units for use in connection with furnaces and stoves of ordinary construction which are already in use.

70

15 The primary object of the invention is to provide a heating device of this character which will eliminate or reduce to a minimum the heat wastage which is prevalent in most types of furnaces and stoves. In other words it is designed to provide a supplemental heater for using the normally wasted heat.

75

20 A further object of the invention is to provide a simply constructed supplemental heating device which can be inexpensively constructed of sheet metal and which can be readily installed without difficulty.

80

25 Another important object of the invention is to provide a device of this character which can be quickly and easily disassembled for the purpose of cleaning.

85

30 With these and other objects in view the invention consists in the novel features of construction, combination and arrangement of parts which will be more particularly described and claimed and shown in the drawings in which:

90

35 Figure 1 represents a horizontal section taken substantially on the plane of the line 1-1 of Fig. 2.

95

40 Fig. 2 is a part sectional and part elevational view of the heater.

100

45 Although the embodiment of the invention illustrated in the accompanying drawing is capable of use in substantially any position, the parts will be referred to in the following explanation of the construction 50 and use of the device as they appear in the drawing. That is to say those parts which are disposed at the top of the structure shown in Fig. 2 will be referred to as upper portions, and the bottom parts as lower portions, etc., this being done for convenience in description. Various changes may be

made in the construction and use of the heater without departing from the principles or sacrificing any of the advantages of the invention.

60

5 Referring more particularly to the accompanying drawing, it will be seen that the invention comprises a portion through which the hot waste gases from the furnace or stove pass, and a portion through which air flows in order to be heated by said gases. Specifically the heater includes an upper head 1, a lower head 2 connected by outer sleeves 3 and 3', and inner sleeves 4. Each of the heads 1 and 2 is preferably formed from a circular sheet metal plate 5 to the periphery of which is secured an annular wall or flange 6, a similarly constructed cover 7 being engaged therewith. It will be noticed that the annular flange of the cover is disposed around the wall 6 and forms a gas-tight joint therewith in the case of both of the heads 1 and 2.

75

10 Each of the covers 7 is detachably secured to its respective head by means of spring arms 8 having laterally extending socket engaging ends 9 which are adapted to be disposed in sockets formed by loops 10. The arms 8 thus form latch members which are designed to be released from an opening 11 formed in each of the circular plates of the covers 7. A chimney-pipe attaching sleeve 12 surrounds each of the openings 11 and is secured to the plate in which the adjacent opening is made. These attaching sleeves 90 extend laterally of the heads 1 and 2, and one provides an intake or supply member for the heater and the other an outlet or exhaust member therefor.

85

15 In the present instance the attaching sleeves 12 are disposed to one side of the center of the covers 7 and are alined with one of the outer sleeves 3', which sleeve does not receive one of the inner sleeves 4 as do the other outer sleeves 3 because of the location of the latch members 8 at the opposite ends of said sleeve 3'.

95

20 In attaching or removing the covers 7 the spring arms 8 may be manually sprung to engage or disengage the keepers 10, the arms being readily accessible through the sleeves 12.

100

25 The hereinbefore referred to inner sleeves 4 are disposed through the outer sleeves 3, but being of a smaller diameter are spaced 110 from the latter. The lower ends of the sleeves 4 are connected with the circular

plate of the lower cover 7 and open there-through, whereas the upper ends thereof terminate inwardly of the similar plate of the upper cover 7 and are designed to tele-scopically receive thimbles 13. These thimbles 13 depend from the upper cover 7, they being carried thereby and opening there-through. Thus in assembled position the inner sleeves 4 and the thimbles 13 provide air passage ways through the heater, while the outer sleeves 3 and 3' circulate the hot gases from one head to the other and around the inner sleeves.

As disclosed in the original patent referred to, the sleeve 3' is provided with a damper as indicated in dotted lines, whereby the smoke of hot products may be controlled so as to cause them to flow directly through the main smoke sleeve 3', or whereby the damper can be closed to cause the products of the combustion to travel in a tortuous route about the various sleeves 4, and from thence back into the upper part of the main sleeve 3'.

In applying this particular type of heater, a section of the ordinary furnace chimney-pipe is removed and the two ends thus formed engaged respectively with the upper and lower attaching sleeves 12. These sleeves 12 being located to one side of the center of the heater as in the present embodiment of the invention, said heater can be readily associated with a chimney-pipe which is located relatively close to a wall or other object. If, however, there is considerable space between the chimney-pipe and such wall, the attaching sleeves 12 may be arranged in the center of the covers 7 so as to provide a slightly more effective distribution of the hot gases from the furnace.

From the foregoing description in connection with the accompanying drawings, it will be obvious that I have invented an extremely simple air heater, which because of such simplicity can be inexpensively manufactured, easily mounted in operative relation with a furnace or stove, and readily cleaned when necessary.

I claim:

1. In a heater, end heads, each of said heads having a removable cover, an outer tubular member connecting the heads to circulate fluid from one to the other, a supply member entering one of the heads, an exhaust member connected with the other head, and an inner tubular member extending through the outer tubular member and opening through each of the heads, said inner tubular member being separable into two sections, one section being secured to each cover and removable therewith.

2. In a heater, end heads, each of said heads having a removable cover, an outer tubular member connecting the heads to circulate fluid from one to the other, a supply member entering one of the heads, an exhaust member connected with the other head, an inner tubular member extending through the outer tubular member and secured at one end to one of said covers, its opposite end terminating within the other head, and a thimble extending into the last mentioned head and carried by the other cover, said thimble being engageable with the last mentioned end of the inner tubular member.

3. In a heater, end heads, each of said heads having a removable cover, an outer tubular member connecting the heads to circulate fluid from one to the other, a supply member entering one of the heads, an exhaust member connected with the other head, an inner tubular member extending from the outer tubular member and secured at one end to one of said covers, its opposite end terminating within the other head, and a thimble extending into the last mentioned head and carried by the other cover, said thimble being engageable with the last mentioned end of the inner tubular member, and means for detachably securing the covers to their respective heads.

In testimony that I claim the foregoing I have hereunto set my hand at Green Lake, in the county of Green Lake and State of Wisconsin.

EZRA T. WHITING.
